DISPLAY BOX

Champe S. Andrews, North Chattanooga, Tenn.

Application April 5, 1932, Serial No. 603,288

7 Claims. (Cl. 229—15)

This invention relates to an improved display box, and more particularly to a box divided into a plurality of cellular spaces adapted to contain various pieces of merchandise in assembled display.

The box herein disclosed includes a box body having a hinged cover stamped from a single sheet of material. A plurality of unitary cells are telescoped into and fit snugly within the box body, when thus arranged the cells greatly reinforce the box and in addition provide means for guiding the cover into closed position and for frictionally holding the cover in closed position. This improved display box can be very economically manufactured and possesses sufficient strength to be effectually used in packaging commodities which have been heretofore packaged only in wooden and metal boxes. The box lends itself to a large variety of attractive designs and may be used to contain and attractively display an assembly or group of different types or varieties of bottled, packaged or unpackaged goods, merchandise and materials, such as pencils, pens, crayons, hairpins, shoe polish, cosmetics, liquid nail polish, facial cream preparations, toilet preparations, medical and surgical preparations or appliances and tools.

An object of this invention is to provide a display box adapted to contain and display group merchandise in an efficient and attractive manner.

A further object of this invention is the provision of a display box comprising an outer container having a hinged cover with a series of cellular members inserted therein each adapted to contain and attractively display an article of merchandise, the cellular members together serving as a reinforcing medium for the container and a guide for the cover.

Another object of this invention is to provide a blank for making the outer container of the improved display box.

Another object of this invention is to provide a blank for making the cellular member of the improved display box.

Another object of this invention is to provide an improved display box which requires a small amount of stock, can be made on automatic cutting and gluing machines with a minimum of hand labor and is otherwise economical to manufacture and produce, which possesses unusual strength and is adequate to support heavy objects heretofore packed only in wood or metal containers, which can be made up in a variety of attractive shapes and designs, and which af-

fords full protection to the contents during shipment and an attractive display when the container is opened to view.

A further object of the invention is the provision of an improved process for making display boxes economically, quickly and expeditiously with a minimum of labor and materials. 5

Other objects of this invention will become apparent as the disclosure proceeds.

Although the novel features which are believed to be characteristic of this invention will be particularly pointed out in the claims appended hereto, the invention itself, as to its objects and advantages, and the manner in which it may be carried out, may be better understood by referring 15 to the following description taken in connection with the accompanying drawing forming a part thereof, in which

Fig. 1 shows a cutout blank from which the body and cover portion of the box may be formed; 20

Fig. 2 shows a cutout blank from which a pair of cellular inserts may be formed;

Fig. 3 is a perspective view of the cellular inserts made from the blank shown in Fig. 2;

Fig. 4 is a perspective view of the completed display box, the cover of the box being open to display a pair of cellular inserts therein; and 25

Fig. 5 is a perspective view of a continuous tubular member and indicates an improved method of making the cellular inserts. 30

Like reference characters refer to similar parts throughout the drawing and specification.

I have shown in Fig. 1 a blank from which the body and cover portion of the box is formed. This blank comprises generally a front wall portion 10, 35 a rear wall portion 11 and end wall portions 12 and 13 hinged together along the score lines 14. In forming the body portion of the container the flap portion 15 hinged to the back portion 11 along the score line 16 is glued or otherwise secured to 40 the free edge of the end wall portion 12. Bottom side wall flaps 17 are hinged, respectively, to the front wall portion 10 and rear wall portion 11 along the score lines 18 and bottom end wall flaps 19 are similarly hinged along score lines 45 20 to the end wall portion 12 and end wall portion 13. The side wall flaps 17 and bottom end wall flaps 19 are turned inwardly, folded one upon the other and glued or otherwise secured together in the well known manner to form the 50 bottom wall of the container.

The cover portion of the box is preferably formed integral with the body portion and comprises rear flange portion 21 hinged to the rear wall box portion 11 along the score line 22. The 55

side flange portion 23 is hinged to the portion 21 along the score line 24. The front flange portion 25 is similarly hinged to portion 23 along the score line 26 and the end flange portion 27 is likewise hinged to the portion 25 along the score line 28, as clearly shown in Fig. 1. End flange portions 23 and 27 and front flange portion 25 are separated from the body portion of the box along the cut 29, as shown in Fig. 1. The cut 29 may be offset as at 30 to provide a suitable finger grip for grasping the cover portion when the box is in set up condition as will be hereinafter described. A flap 31 hinged along the score line 32 to the rear flange portion 21 may be glued or otherwise secured to the free edge of the end flange portion 27. The cover flaps 33 hinged to the side flange portions 21 and 25 along the score lines 34, and the end flaps 35 hinged to the end flange portions 23 and 27 along the score lines 36 may be folded inwardly in superimposed relationship and secured together by cement or other means to form the top wall of the box.

The outer container above described may be divided into any number of separate chambers or units. To this end there is provided a cellular insert which is placed within the outer container. The cellular insert may comprise any desired number of separate cells or chambers, as will appear hereafter. For purposes of illustration only, the cellular insert shown in the drawing comprises two units, but it is appreciated that any number of units in any desired size and capacity may be used. Referring to Fig. 2 of the drawing, the cellular insert may be formed from a blank which comprises front wall portions 51, side wall portions 52 and 53, back wall portions 54 and securing tabs 55. The front wall portions 51, side wall portions 52 and rear wall portions are completely separated at their abutting ends into pairs by a cut 56, while the paired side wall portions 53 are hinged together along the score line 57. The front, side and end wall portions are separated along the sides by the score lines 58, as clearly shown in Fig. 2.

The rear wall portions 54 may be longer than the front wall portions 51 and may also be provided with a rounded cutout top edge 59 to facilitate grasping the contents in the set up container, as will more clearly appear hereinafter. One end of the side wall portions 52 and 53 may be provided with tapered edges 60 and in addition the edge 60 of the side wall portion 53 may be notched out as at 61 to further facilitate the removal of the contents. All of the scores and cutouts referred to above and shown in Fig. 2 may be made in one operation as the roll of sheet material is fed through the scoring and cutting machine.

In forming the cellular insert the blank shown in Fig. 2 is folded along the score lines 58 into tubular form and the tabs 55 are then glued, stapled or otherwise secured to the free edges 62 of the side wall portions 52. The tube thus formed may be bent along the score line 57, as shown in Fig. 3, so that the side wall portions 53 are in contact with one another. The completed cellular insert may now be telescoped into the outer container, as shown in Fig. 4, and are of such size as to snugly fit therein, thus providing substantial reinforcement to the outer container. The upper end of the cellular units project above the top edge 40 of the outer container to form a collar over which the cover telescopes. The frictional contact between the side walls of the cover 75 and the collar portion thus provided holds the

cover in place when moved into closed position.

It is now seen that this cellular insert may be made rapidly and economically from a single cut and scored blank, which is cut from a continuous ribbon of paper stock. The blank thus prepared may be automatically assembled by a single folding and securing operation.

Referring now to Fig. 5, there is shown a substantially continuous tubular member having the cross-sectional configuration and shape of the cellular units shown in Figs. 3 and 4. This member may be formed as a continuous tube of any desired cross-sectional shape, but is shown in Fig. 5 as rectangular in cross-section for purposes of illustration only. As shown the tube is made from a continuous strip of material having the side wall portions 70, 71, 72 and 73 and a securing tab portion 74 all separated by longitudinally extending score lines 75. The side wall portions 70 are separated into segments by the spaced transverse scores 76 and the side wall portions 71, 72 and 73 are severed into segments by the transverse cuts 77. The blank is then formed into a tube by folding the same along the score lines 75, as clearly shown in Fig. 5, and the tab 74 is then secured by glue, staples or other means to the free edge 78 of the side wall portion 70.

In making the cellular inserts from the tube shown in Fig. 5, the tube is sawed off at an oblique angle at intervals between the score lines 75 so as to provide a chamfered edge 79 to the side wall portions 70 and 72. A cutout finger recess (not shown) may be provided along the top edge of the side wall portion 73 if desired. It is now seen that the units so made can be folded together along the score line 76 so that the side wall portions 70 are in contact. From a proper arrangement of the score lines and cuts it is seen that any number of units may be linked together by a score line hinged so as to provide a battery 40 of cells for insertion into the outer container. The cellular inserts made as illustrated in Fig. 5 can be economically manufactured on automatic machines with the least possible waste of material.

The battery of cells when inserted into the container not only provides cover guides and cover retention means, but adds considerable strength to the body portion of the outer container. The entire box is adapted for automatic machine production and can be made completely on a blank forming machine and a gluing machine such as are in general use. It will be seen that there is little or no waste of material in the formation of my box, both the box and cover forming blank and the cell-forming blank being substantially rectangular in shape. The cellular inserts may also be formed from a continuous tubular member of any desired configuration. The box and cellular inserts may be made from a variety of materials, such as paper or fiber board and are sturdily reinforced at all points of strain. If the paper material is of good quality, the box can be made sufficiently strong to serve uses where wood and metal boxes only have been used heretofore. The box may be made in a large variety of pleasing designs so as to display the contents in an attractive and advantageous manner.

While certain novel features of the invention have been disclosed and are pointed out in the annexed claims, it will be understood that various omissions, substitutions and changes may be made by those skilled in the art without departing from the spirit of the invention.

What is claimed is:

1. A box of the character described comprising, body and cover portions formed from a single piece of paper material, and a separate multi-tubular collar member formed from a single piece of material snugly fitting within said body portion, resting on the bottom of said body portion and projecting above the body portion, said collar member being adapted to frictionally retain the cover portion in closed position. 5
2. A box of the character described comprising, body and cover portions formed from a single piece of paper material, said body portion comprising side walls and bottom flaps forming the bottom wall of the box, and said cover portion comprising side flanges and top flaps forming the top wall of the box, one of said side flanges being integral with and a continuation of a side wall of the box portion, and a separate multi-tubular collar member inserted within the body portion and adapted to frictionally retain the cover portion in closed position, said collar member resting on the bottom wall of the body portion. 10
3. A box of the character described comprising, in combination body and cover portions formed from a single piece of paper material, said body portion comprising side walls and bottom flaps forming the bottom wall of the box, said cover portion comprising side flanges and top flaps forming the top wall of the box, one of said side flanges being integral with and a continuation of a side wall of the box portion, and a plurality of connected tubular units formed from a single piece of paper material inserted within the body portion and forming a collar portion adapted to frictionally retain the cover portion in closed position, said tubular units resting on said bottom wall. 15
4. A box of the character described comprising, body and cover portions formed from a single piece of paper material, said body portion comprising side walls and bottom flaps forming the bottom wall of the box, and said cover portion comprising side flanges and top flaps forming the top wall of the box, one of said flanges being integral with and a continuation of a side wall of the box portion, and a pair of connected tubular units formed from a single piece of paper material within said body portion adapted to frictionally retain the cover portion in closed position, said tubular units resting on said bottom wall. 20
5. A box of the character described comprising, body and cover portions formed from a single piece of paper material, said body portion comprising side walls and bottom flaps forming the bottom wall of the box, said cover portion comprising side flanges and top flaps forming the top wall of the box, one of said side flanges being integral with and a continuation of a side wall of the box portion, and a plurality of tubular units frictionally retained in position within said body portion, said tubular units being formed from a separate single piece of material and centrally bent into abutting relation with each other and adapted to frictionally retain the cover portion in closed position, said units resting on said bottom wall. 25
6. A box of the character described comprising, body and cover portions formed from a single piece of paper material, said body portion comprising side walls and bottom flaps forming the bottom wall of the box, said cover portion comprising side flanges and top flaps forming the top wall of the box, one of said side flanges being integral with and a continuation of a side wall of the box portion, and a separate multi-tubular insert member snugly fitting within and reinforcing said body portion, said insert member having one end thereof resting on the bottom of the body portion and the other end projecting above the body portion, to provide a collar portion adapted to frictionally engage the cover portion to retain the same in closed position, the top edges of the insert member being cut at an angle whereby the rear edges of the insert members are higher than the front edges of said members. 30
7. A box of the character described comprising, body and cover portions formed from a single piece of paper material, said body portion comprising side walls and bottom flaps forming the bottom wall of the box, said cover portion comprising side flanges and top flaps forming the top wall of the box, one of said side flanges being integral with and a continuation of a side wall of the box portion, and a separate tubular insert member snugly fitting within and reinforcing said body portion, said insert member having one end thereof resting on the bottom of the body portion and the other end projecting above the body portion to provide a collar portion adapted to frictionally engage the cover portion to retain the same in closed position. 35
